GUIDE FOR ELECTRODE MOUNTS

Harold E. Baker, Danvers, and Charles A. Young,
Gloucester, Mass., assignors to Sylvania Electric Products Inc., Salem, Mass., a corporation of Massachusetts

Application December 17, 1949, Serial No. 133,602

5 Claims. (Cl. 49—2)

1

This invention relates to electric lamp manufacturing equipment, and more particularly to lamp sealing machines.

In the manufacture of fluorescent lamps, electrode mounts are sealed in the ends of an elongated glass tube on the lamp sealing machine. The component parts, i. e., the electrode mounts and the elongated glass tubes are fed to the lamp sealing machine, manually or mechanically, where they are properly positioned with reference to one another for the sealing operation. When a high speed lamp sealing machine is employed, the electrode mounts and the elongated glass tubes must be fed thereto rapidly. Since some electrode mounts have an exhaust tube as well as lead wires, the speed at which a lamp sealing machine may be operated is determined in large part by the speed with which electrode mounts may be fed to and accurately seated on their supports on the lamp sealing machine.

An object of this invention is to provide a mechanism whereby the speed with which electrode mounts may be fed to and accurately seated on their supports on a lamp sealing machine may be increased.

Another object is to provide a mechanism for automatically effecting proper positioning of the exhaust tube and lead wires of an electrode mount for the threading thereof into the mount support on the lamp sealing machine.

Further objects, advantages and features will be apparent from the following description thereof, when read in conjunction with the accompanying drawing in which:

Figure 1 is a fragmentary top plan view of a lamp sealing machine, showing two of the lamp sealing machine heads.

Figure 2 is a side elevational view in section taken along the lines 2—2 of Figure 1.

Figure 3 is a fragmentary top plan view with the lamp sealing machine and the heads in phantom for clarity.

The lamp sealing machine with which the apparatus of this invention may be employed may be of the type shown in U. S. Patent 2,349,822 for example. The lamp sealing machine comprises a turntable 1 with a plurality of heads 2 (two of which are shown in the drawing) supported from the periphery thereof by brackets 3. Each head 2 has a centrally disposed aperture therein into which the shank 4 of a mount pin 5 extends. The head 6 of the mount pin 5 is a serrated frustro-conical member which defines a seat for an electrode mount. Each lamp sealing head 2 has a burner 7 which is concentric with the

2

shank 4 of the mount pin 5. The burner 7 has a plurality of ports 8 disposed radially thereabout. The mount pin 5 is a hollow member defining a chamber into which the lead wires 9 and exhaust tube 10 of an electrode mount 11 are threaded. In addition to the lead wires 9 and the exhaust tube 10, the electrode mount 11 comprises a flare 12, a stem press 13 through which lead wires 9 are sealed and in which an exhaust port 14 is blown, and an electrode 15 mounted on the lead wires 9. A glass-working ring 16 is disposed on the top of the lamp sealing head 2.

The mount guide of this invention comprises a pair of coaxing plates 50 and 51 with a depending frustro-conical central portion 17 which define a funnel 18. Plate 50 has a shank portion 23 which is attached to a support 19. Plate 51 is pivotally mounted at 20 on plate 50, thereby defining a gate in the funnel. An arm, such as a stiff wire member 21, for example, is attached at one end thereof to the periphery of plate 51 and extends about the major portion of the periphery of the funnel 18. A spring 22, attached at one end thereof to a pin 20 upstanding on the shank 23 of plate 50, is connected to the free end of the stiff wire member 21. Plate 50 has a rod 60 attached to the periphery thereof and extending on an inclined plane therefrom.

In the drawing, two of the plurality of heads 2 mounted about the periphery of the turntable 1 of the lamp sealing machine are illustrated. The turntable 1 carries the heads 2 through a plurality of stations at which various steps in the lamp sealing operation are performed. In the drawings, station A is the mount feeding station and station B is the first station at which the electrode mount is seated on the mount pin 5. The mount-guiding funnel 18 is mounted at station A and is disposed so that its aperture 24 is above and in register with the aperture in the mount pin 5 of a lamp sealing head 2 when the head is at station A. The aperture in the funnel 18 is no larger in diameter than the aperture in the mount pin 5 and is preferably smaller to insure proper threading of the exhaust tube 10 and lead wires 9.

The mount guide of this invention may be employed advantageously whether the mounts be fed to the sealing machine manually or mechanically. However, it is particularly advantageous in the case of mechanical feeding at speeds greater than the speed with which an operator can satisfactorily perform the operation.

In operation, an electrode mount 11 is seated

on the funnel 18 by inserting the exhaust tube 10 and lead wires 9 thereof into the frustro-conical central portion 17 of the funnel 18. Because of its contour and the diameter of the aperture 24, the funnel automatically threads the exhaust tube 10 and the lead wires 9 into the chamber therefor in the mount pin 5, and the flare 12 comes to rest on the plates 50 and 51 of the funnel (Figure 2, station A). The lamp sealing machine now indexes and carries the lamp sealing head from station A to station B. During the course of its travel from station A to station B the electrode mount 11, guided by the inclined rod 60, gradually drops down until it seats itself on the mount pin 5.

In order for the mount 11 to move with the head into which its exhaust tube and lead wires were partially threaded, the funnel 18 must be opened. Movement of the lamp sealing machine head 2 from station A causes a force to be applied through the exhaust tube 10 on the frustro-conical central portion 17 of the funnel 18. This force is sufficient to displace the plate 51, which functions as a gate pivoting about point 52, in a counter-clockwise direction a distance sufficient to permit the exhaust tube 10 and lead wires 9 to pass between the normally closed adjacent faces of plates 50 and 51 (Figure 3, station A).

As the plate 51 moves in a counter-clockwise direction, the stiff wire member 21 is moved in a similar direction, thereby distending the spring 22. After the exhaust tube 10 and lead wires 9 have moved beyond the periphery of the funnel 18, the spring 22 effects a closing of the plate 51 with the plate 50.

It will be noted from the drawing, particularly Figures 1 and 3, station A, that the aperture 24 at the truncated apex of the frustro-conical central portion 17 of the funnel 18 is not truly circular in contour. Deviation from truly circular configuration occurs at the adjacent faces of plates 50 and 51 which part to provide a path of travel for the exhaust tube 10 and the lead wires 9, the portion 34 being tangential and the portion 35 being rounded. This configuration has been found to be more advantageous than a truly circular contour because it minimizes the possibility of one or both of the lead wires being caught therein and drawn out of position during the travel of the exhaust tube 10 and lead wires 9 through the path provided for them when the plate 51 swings counter-clockwise.

What we claim is:

1. Apparatus for threading the lead wires and exhaust tube of an electrode mount into a chamber therefor in a mount pin of a lamp sealing

machine, said apparatus comprising: a funnel having a normally closed gate portion hinged thereon; an arm mounted on said gate portion and extending about a portion of the periphery of said funnel; and means for actuating said arm to effect a closing of said gate after it has been opened.

2. Apparatus for positioning an electrode mount on a mount pin of a lamp sealing machine, said apparatus comprising: a funnel having a normally closed gate portion; means for automatically closing said gate after it has been opened; and a guide track extending outwardly and downwardly from the periphery of said funnel.

3. Apparatus for positioning an electrode mount on a mount pin of a lamp sealing machine, said apparatus comprising: a funnel having a normally closed gate portion, the diameter of the outlet of the funnel being no greater than the diameter of the chamber in the mount pin; means for automatically closing said gate after it has been opened; and a guide track extending outwardly and downwardly from the periphery of said funnel.

4. Apparatus for positioning an electrode mount on a mount pin of a lamp sealing machine, said apparatus comprising: a funnel having a normally closed gate portion; an arm mounted on said gate portion; means for actuating said arm to effect a closing of said gate after it has been opened; and a guide track extending outwardly and downwardly from the periphery of said funnel.

5. Apparatus for positioning an electrode mount on a mount pin of a lamp sealing machine, said apparatus comprising: a funnel having a normally closed gate portion hinged thereon; and a resilient arm attached to the periphery of said funnel and extending about a portion thereof including a portion of the periphery of said gate and in contact therewith to effect a closing of said gate after it has been opened.
